UNITED STATES PATENT OFFICE

CHARLES HENRY COCHRANE, OF NEW YORK, N. Y.

COMBINED INK DRYING AND NEUTRALIZING DEVICE

Application filed November 26, 1930. Serial No. 498,399.

My invention relates to improvements in devices for electrically drying ink on printed paper sheets and at the same time remove or neutralize static electric charges in the paper sheets, as experienced in the operation of printing presses and paper handling machines.

The objects of this invention are as follows:

First.—To provide a simple and efficient device producing strong electrical breezes in close proximity of freshly printed paper, for the purpose of rapidly oxidizing the ink and thereby greatly facilitating the drying process.

Second.—To utilize the same device to dissipate or neutralize any static electric charge that may be present or develop in the paper.

Third.—To provide a large number of specially designed electrical breeze-producing members of comparatively small individual electrical capacity.

Fourth.—To provide a simple and effective protecting and insulating means to positively prevent the electrically charged breeze-producing members from being touched or tampered with.

Fifth.—To provide suitably interwoven insulating and spacing means for the purpose of preventing any possible displacement of the individual electrical breeze-producing members.

Sixth.—To provide certain mounting means whereby the device may be easily attached or detached to or from any standard printing or paper-handling machine.

Seventh.—To produce a device of simple and inexpensive construction, to permit the manufacture of the same in large quantities and at the possible lowest cost.

These and other objects I attain by the novel combination of various parts and elements, fully described in this specification and illustrated in the accompanying drawing in which:

Figure 1 represents a front elevation and diagram of the electrical connections of a combined electrical drying and neutralizing device embodying the features of my invention.

Figures 2, 3 and 4, represent detailed views

of various electrical breeze-producing members.

Figures 5, 6 and 7, represent detailed views of the general construction.

It is a well known fact that in the operation of modern high speed printing presses and paper-handling machines numerous serious difficulties must be overcome. By far the most important difficulties are: first, the comparatively slow drying process of the printed ink, second, the high degree of static electricity developed in the paper. The methods commonly employed to overcome these disadvantages, are gas or electrically operated heating devices, for the drying process, and the so-called neutralizer, another electrical device to dissipate the electrical charges accumulated in the paper.

In practice I have found that the ink drying devices, employed at present, develop a very high degree of temperature, thus not only rendering the device difficult to apply and operate, but are an ever-present source of danger, being near to the highly inflammable paper materials.

The so-called neutralizers, at present utilized to dissipate the static electrical charges, are designed to produce a concentrated alternating electrical field of high potential and high capacity require the utmost care to provide adequate protection against accidental touch and contact.

Now, I discovered that by reducing the individual electrical capacity and considerably increasing the number of the electrical breeze-producing members I am able to create a widely diffused field of electrical charges manifesting themselves in the form of electrical breezes. These electrical breezes not only will effectively dissipate or neutralize the static electrical charges but also cause the printed ink to instantly oxidize, or in other words form a slight film upon its surface, thus eliminating the dangerous method of drying by artificial heat.

The electrical breezes are created by the inductive action of a conductor charged with high voltage alternating energy upon a large number of properly arranged inductive members of low electrical capacity.

In Figure 1 I have illustrated a device embodying the features of such a combined ink drying and neutralizing arrangement actuated by electrical breezes. A source of low tension alternating current, provided either directly from an alternating current light or power system, or indirectly by a motor generator arrangement A, as illustrated, is connected to a high tension transformer B, the secondary coil of which is designed to provide an electric current of high potential usually 20,000 volts. Electrical conductor 1, of the combined ink drying and neutralizing device, is charged with this high potential energy, which by induction is transferred to the individual members 3. Conductor 1 is suitably covered by a heavy insulating jacket 2 upon which a very large number of the inductive breeze-producing members 3 are permanently positioned and protected by a suitable insulating covering 4a. Another protective split jacket 5 of insulating material and a pair of suitably arranged mounting brackets 6, complete the arrangement.

In Figures 2, 3 and 4 inductive members of various design are shown. In Figure 2 the inductive member, made of metallic rod or wire, comprises a loop 3a and the straight diffusing part 3b.

It will be noted that the loop part 3a embraces but a small area of active charging surface, thus reducing the individual potential charge to a much lower value than hitherto practiced. In Figure 3 the same member as in Figure 2 is shown with the exception that the charging capacity is doubled by providing two loops 3a and 3a¹. Figure 4 shows a means of insulating the individual members by a covering 7, of insulating material. In Figures 5, 6 and 7 a more detailed illustration of the method of assembling and insulating the prime conductor and the individual inductive members of the device are shown. The inductive members are designed to closely grip and hold by friction upon the insulating covering 2. A sheet of insulating material 4b is suitably woven between the alternating members 3b, thereby effectively insulating and spacing the individual members. Another insulating covering 4a is folded over the inner structure as shown in Figures 6 and 7, thus fully enclosing and protecting the metallic members 3 from touch or injury. A slotted insulating jacket 5 serving as a holding and protective means is finally attached for the purpose of holding the various members securely in position.

Having thus fully described and illustrated my invention I do not wish to confine myself to the exact details of construction, it being apparent that there may be considerable variations possible without departing from the spirit of my invention.

I claim:

1. In a device of the character described

the combination of a suitable electrical conductor, said electrical conductor being charged with high potential alternating electrical energy, a suitable insulating covering embracing said electrical conductor, and a plurality of suitably shaped inductive electrical members positioned and held upon said insulating covering for the purpose of creating electrical breezes, and insulating means to completely cover and protect said plurality of inductive electrical members. 75

2. In a device of the character described the combination of an electrical conductor, said electrical conductor being subject to charges of high potential alternating electrical energy, an insulating covering embracing said conductor, and a plurality of suitably shaped inductive metallic members of low electrical capacity positioned and held in close proximity upon said insulating covering to serve the purpose of producing a diffused field of electrical breezes, and suitable interwoven insulating means to laterally space said plurality of inductive metallic members, and folded insulating means to completely encase and protect said metallic inductive members. 80

3. In a device of the character described the combination of an electrical conductor, said conductor subject to charges of high potential alternating electrical energy, an insulating covering surrounding said conductor, and a plurality of metallic inductive members of low electrical capacity positioned and held by means of a suitably interwoven insulating member in close lateral proximity upon said insulating covering, and said metallic inductive members comprising a looped charging portion terminating into a straight electrical diffusing portion, and said looped portion disposed to surround and grip said insulating covering, and a folded insulating member to completely enclose and protect said metallic inductive members substantially as and for the purpose set forth. 95

4. In a device of the character described the combination of a suitable electrical conductor, a suitable insulating covering encasing said conductor, a plurality of looped inductive charging members suitably spaced and held upon said insulating covering, and a longitudinally and centrally positioned insulating strip member threaded between the inductive charging members, and an insulating protecting cover member to completely encase said charging members, and said insulating cover member folded around and over said charging members and held in position by a longitudinally slotted insulating sleeve member, substantially as and for the purpose set forth. 110

5. In combination with printing presses and paper handling machines a source of high tension alternating electric current, said high tension alternating current electrical- 125

- ly connected to an insulated cable conductor positioned in close proximity of the moving paper, and said insulated cable carrying a plurality of inductive looped metal pins for the purpose of producing inductive electrical breezes to rapidly dry the freshly printed ink and at the same time dissipate static electric charges in the issuing paper, said plurality of looped metal pins laterally spaced and held in position by interweaving a strip of insulating material, and a sheet of insulating material folded over and completely enclosing said looped metal pins, substantially as and for the purpose set forth.
- 15 6. In a device for neutralizing electrical charges in sheets of paper and simultaneously oxidizing freshly printed ink upon the paper, the combination of a high tension transformer or other source of alternating current, a suitably insulated cable conductor electrically charged by said source of high tension alternating current, a series of metallic inductive electrical breeze-producing looped pins positioned and held upon said insulated cable, by means of a suitably interwoven strip of insulating material, a sheet of insulating material folded over and completely enclosing said looped pins, and insulating and mounting means for the purpose of protecting and attaching the device to paper handling machines.
